C. RIDDLE

DIGESTER

Filed July 11, 1925

INVENTOR.

CARLTON RIDDLE

BY ATTORNEY.

Patented Aug. 16, 1927.

UNITED STATES PATENT OFFICE.

CARLTON RIDDLE, OF AKRON, OHIO, ASSIGNOR TO THE MCNEIL BOILER COMPANY, OF AKRON, OHIO, A CORPORATION OF OHIO.

DIGESTER.

Application filed July 11, 1925. Serial No. 43,042.

This invention relates to a jacketed vessel suitable for use in many industries, the object of the invention being to design a double walled vessel of improved construction which will withstand high pressures. It is also an object of the invention to design a digester of this type which can be easily cleaned. Other objects and advantages are obtained in the new form of apparatus shown and described, it being understood that the invention is not limited to the exact details but may be modified within the scope of the claims.

In the drawings are shown two forms of the invention, the first being a digester or tank of the tumbling variety in which the device is provided with means by which it can be rotated. A longitudinal section is shown in Figure 1. A detail of the tank wall is shown in Figure 2, and in Figure 3 is shown a modification of the steam inlet.

Figure 4 is a section of the tank of the stationary type in which there are provided stirring shafts for agitating the mass within the digester.

The present invention may be used in numerous arts, such, for example, in the digesting of stock for paper manufacture, or in the treatment of waste rubber for reclaiming purposes. Other uses will be apparent from a description of the device and it is not desired to limit the invention to any particular art or industry.

One of the chief objects of the invention is to provide a device of this character in which the tank is double walled and to permit the introduction of steam to either the outer jacket or the inner portion of the tank as the particular work may require, and in which the walls of the inner tank are so constructed as to permit of expansion and contraction without danger of loosening the tank walls. For this purpose the outer wall of the tank is in the form of a cylinder 1 of heavy steel construction provided with heads 2 which are riveted to the main body of the tank and carry trunnions 3 which form the support for the tank in uprights 4. The body of the tank is provided with a charging door 5 and a discharge 6, both suitably closed, being located midway of the tank.

The inner wall or lining to the tank is formed from two circumferentially corrugated steel shells 7, which are riveted to the

tank body at either side of the openings 5 and 6, so that the openings pass through the single outer wall only. The corrugated construction of the inner shells 7 secure a greater heat radiation from the jacketed space, and it will be noted that the shells are attached to the tank at their ends adjacent the doors, the outer ends of the shells being permitted to expand and contract freely and being supported for this purpose within a recess 10 in the trunnion 3. The shells are riveted at their ends to heads 11 and at the center are provided with a central bearing plate 12 which is formed with an extension 13 which is slidably received within the recess 10, the projection being provided with grooves 15 which admit steam from the center of the trunnion to the jacketed space between the walls 1 and 7.

For washing out the tank there are provided two perforated flush pipes 18 which are provided with angular extensions 19 which discharge on the bottom of the shell near the end wall 11. In order to prevent the retention of the contents of the tank within the shell, the corrugations are filled up at the bottom of the tank. In the present embodiment of the invention, there are provided a plurality of fillers or inserts 20 which are situated within the corrugations and extend up along the walls a short distance and prevent the collection of liquid or sediment within the corrugations. This is an especially valuable feature of the invention as it removes all of the old material before the introduction of a new batch.

So far as has been described, both ends of the digester are the same. One of the trunnions, here shown as the left hand trunnion, is provided with a driving gear 25 driven by a spur gear 26 from the drive shaft 27. Drains 29 for the outer jacket are connected to a drain pipe 30 which discharges through the left hand trunnion and out through a steam trap 31. Steam to the outer jacket is admitted through inlets 32 which conduct the steam into the interior of the trunnions and through the grooves 15, packings 33 being located at the outside of the trunnions. Steam for the interior of the digester is admitted through a steam inlet pipe 35 which is packed, as at 36, on the interior of the central gearing plate 12.

In order to avoid packing located internally of the tank, the construction may be

modified as shown in Figure 3, in which the packing 36 is replaced by a packing 38 located outside of the steam pipe 32.

If a non-rotating drum provided with agitating devices is desired, the tank is mounted on supports 40 and through the axis of the tank is located a shaft 41 provided with vanes or paddles 42 and driven by a gear 43. The steam inlets for the jackets may be arranged above the tank as shown at 44.

What is claimed is:

1. In a digester for the uses and purposes set forth, a tank having inlet and outlet ports in the central region thereof, shells located within the tank at either side of said ports, the shells being secured directly to the wall of the tank about circumferential lines at either side of the ports, and supports for the ends of the shells at either end 20 of the tank, said supports permitting expansion and contraction of the shells independently of the tank.

2. In a digester for the uses and purposes set forth, a tank having inlet and outlet 25 ports arranged in the central region thereof, shells located within the tank, said shells being riveted to the wall of the tank adjacent the ports, the walls of said shells being corrugated, a central bearing plate located in 30 the end of each shell, a sliding support for said bearing plate, and means for introducing steam within the jackets formed between the outer wall of the tank and the shells.

3. In a digester for the uses and purposes 35 set forth, a cylindrical tank having inlet and outlet ports arranged centrally thereof, shells having corrugated walls and riveted to the interior of the tank adjacent the ports, a trunnion at each end of the tank, and a 40 bearing plate on the end of each shell having an extension slidably received within the trunnion.

4. A digester for the uses and purposes set forth, the axis of which is horizontal, the 45 inner wall of which is circumferentially corrugated, and filler strips within the corrugations along the bottom of the digester.

5. A digester for the uses and purposes set forth, the axis of which is horizontal, the 50 inner wall of which is circumferentially corrugated, filler strips within the corrugations along the bottom of the digester, and means to flush said digester.

6. A digester for the uses and purposes set 55 forth, comprising a horizontally arranged tank, an inner shell within the tank, the

walls of which are corrugated, and filler strips within the corrugations at the bottom of the shell to prevent accumulation of the 60 contents of the shell.

7. A digester for the uses and purposes set forth, comprising a horizontal shell, the inner surface of which is corrugated except along the bottom of the shell.

8. A digester for the uses and purposes set forth, comprising a horizontal shell, the inner surface of which is provided with circumferential corrugations except along the bottom of the shell.

9. A digester for the uses and purposes set forth, comprising a horizontal cylindrical tank, two oppositely positioned corrugated shells riveted to the tank, a central bearing plate on each shell having a projection extending therefrom, and a support at each 75 end of the tank adapted to receive the projection and permit movement thereof.

10. In a digester for the uses and purposes set forth, a tank having inlet and outlet 80 ports in the central region thereof, shells located within the tank at either side of said ports, the shells being secured to the wall of the tank about spaced circumferential lines at either side of the ports, thereby exposing a belt about the inner surface of the tank, a bearing at the end of each shell, sliding supports for said bearings, and means for introducing steam about the shells.

11. A digester for the uses and purposes set forth, comprising an outer tank, two 85 spaced inner shells within said tank and riveted thereto in the region adjacent the center of the tank, inlet and outlet ports between the shells, steam inlets to the spaces between the tank and the shells, a central bearing 90 plate in the end of each shell slidably supported by the tank, a steam inlet passing through the bearing plate at an end of the shell, the walls of the shells being corrugated circumferentially, filler plates within the 95 corrugations at the bottom of the shells, and flush pipes at the end of each shell.

12. A digester for the uses and purposes set forth, comprising a horizontal cylindrical tank having an inner and outer wall, the 100 inner wall having a plurality of parallel corrugations extending circumferentially of the tank and an opening passing through the walls, the inner wall being secured to the outer wall adjacent the opening and free to 105 expand along the axis of the tank.

CARLTON RIDDELL.
